Primary Examiner — Kevin Rudzinski*Assistant Examiner* — John Reickel(74) *Attorney, Agent, or Firm* — Knobbe Martens Olson & Bear LLP(57) **CLAIM**

The ornamental design for a display screen with graphic user interface, as shown and described.

DESCRIPTION

FIG. 1 is a front elevational view of a display screen with graphic user interface showing our new design.

FIG. 2 is front elevational view of a second embodiment thereof.

FIG. 3 is front elevational view of a third embodiment thereof.

FIG. 4 is front elevational view of a fourth embodiment thereof.

FIG. 5 is front elevational view of a fifth embodiment thereof.

FIG. 6 is front elevational view of a sixth embodiment thereof; and,

FIG. 7 is front elevational view of a seventh embodiment thereof.

The broken lines depict environmental details of the display screen and of the graphic user interface that form no part of the claimed design.
